CLAIM

The ornamental design for an on-body injector for drug delivery, as shown and described.

DESCRIPTION

FIG. 1 is a perspective view showing a new design for an on-body injector for drug delivery; FIG. 2 is a top view of the on-body injector of FIG. 1; FIG. 3 is a bottom view of the on-body injector of FIG. 1; FIG. 4 is a right-side view of the on-body injector of FIG. 1;

FIG. 5 is a left-side view of the on-body injector of FIG. 1; FIG. 6 is a back view of the on-body injector of FIG. 1; and, FIG. 7 is a front view of the on-body injector of FIG. 1. The broken lines show portions of the design that form no part of the claimed design.

1 Claim, 3 Drawing Sheets
